UNITED STATES PATENT OFFICE

2,612,615

CATHODE FOR IONIZATION DETECTION
DEVICES

Edith B. Fehr and William T. Posey, Schenectady,
N. Y., assignors to General Electric Company,
a corporation of New York

Application July 22, 1949, Serial No. 106,286

4 Claims. (Cl. 313—93)

1

This invention relates to ionization detection devices. More particularly it relates to a cathode for ionization detection devices having a halogen-containing atmosphere.

Many gases have been proposed and are known to be suitable for use in ionization detection devices and more particularly in the type of device known as the Geiger-Müller counter. Among these gases are argon, helium, xenon, neon, krypton, nitrogen, hydrogen, methane, oxygen and the vapors of various organic compounds such as the alcohols illustrated by ethyl and methyl alcohols among others. These gases are used either singly or in combination to obtain different operating characteristics.

It has also been proposed to use a gas of the halogen group, e.g., chlorine or halogen-containing gases in combination with other inert gases. Such combinations of gases produce ionization detection device atmospheres which will not degenerate under over-voltage impulses as do the alcohols, for example. Ionization detection devices containing a halogen gas are also characterized by a self-quenching quality which has previously been associated only with polyatomic gases such as alcohol vapors containing four or more atoms. Further, since the halogen gas does not break down permanently into simpler components as do the alcohols during the self-quenching process, counting devices employing the halogens in their atmospheres have an almost unlimited life.

The amount of halogen gas required to attain the beneficial results afforded is very critical and very small, 0.1 per cent to about 0.2 percent by volume being all that is generally required. Thus a typical counter atmosphere composition might consist of one volume of chlorine or other halogen gas or mixtures thereof, 760 volumes of neon gas and four volumes of argon gas, this example being only illustrative; other inert gases as well as the above being capable of use in varying proportions so long as the halogen gas is kept within its limits. While the halogen gases afford certain advantages in ionization detection devices, they are very corrosive to and combine with metal with resultant loss of the beneficial effect of the gas when the usual metal cathodes are used. Metals presently used as cathodes in counters having a halogen-containing atmosphere must be specially processed and treated as, for example, by careful polishing to close all inter-crystalline spaces or pores and then oxidized. However, even the most careful preparation of

the metal cathode material fails to protect against the corrosive action of the halogens for any suitable length of time.

It is an object of this invention to provide a suitable cathode for ionization detection devices containing halogen gases.

It is another object of the present invention to provide a cathode for ionization detection devices which shall be non-corroding in the presence of halogen gases or halogen-containing gases.

It is a further object of the invention to utilize as a cathode the envelope of the ionization detection device which is composed of a treated glass, vitreous or ceramic material.

Other objects will become apparent from a consideration of the following description and the drawing in which Fig. 1 represents a cross-sectional view of a typical ionization detection device employing the cathode film of the present invention; Fig. 2 is a cross-sectional view of another device using the film and Fig. 3 shows a typical electrical circuit employing a counter embodying the present cathode.

It has been found that non-corroding cathodes for ionization detection devices containing halogen gases may be produced by using as cathodes, coatings of films containing a halogen-resistant electrically conductive material.

More particularly it has been found that non-corroding and non-halogen absorbing cathodes for ionization detection devices may be produced by using as cathodes glass, vitreous or ceramic envelope material and covering the inner surface thereof with electrically conductive materials made by treating the surface with a metal halide. The metal halide preferably should have a boiling point below the temperature at which the coating is formed on the envelope. It is most convenient to use tin halide as the treating agent although other halides such as those of iron, titanium, columbium, aluminum and tantalum among others may also be used. Tin chloride is the preferred treating agent and is used in the example below, though it is to be understood that other halides of tin may be used as well as halides of other metals such as those listed above and which boil at a temperature below that of the heated envelope.

The preferred tin chloride may be placed on the inner wall of the counter or ionization detector in any convenient manner. Thus liquid tin chloride may be sprayed onto the heated surface of the counter chamber. Alternatively, vaporized tin chloride may be introduced into the heated

tube or envelope to give the same effect. Preferably the tin chloride is dissolved in alcohol or an alcohol-water solution and sprayed into the vitreous counter chamber or envelope which is maintained at a temperature of about 400° C. to 700° C. and preferably at least 500° C. The concentration of tin chloride in the alcohol may vary widely, the smaller the concentration of the chloride, the more the amount of solution which is required. A preferred spraying solution consists of fifty parts by weight of tin chloride dissolved in forty-five parts by weight of ethyl alcohol.

The exact nature or character of the conductive film produced on the heated glass, vitreous or ceramic wall by the tin chloride or other metal halides is not known. Analysis has shown that the film has no halide content. The tin or other metal, which is known to be present, is in combined form, perhaps as a tin or metal oxide, or even conceivably in combination with the constituents of the vitreous surface. The absence of the usual gray cast of elemental metal militates against the presence of tin or other metal in this state on the envelope wall.

Attention is invited to the drawing for typical examples of the use of the present cathode film in counter devices. In Fig. 1 is shown a radiation or ionization measuring device, or counter of the Geiger-Müller type. The tube or envelope 1 of the counter is fabricated of non-conducting vitreous material such as glass or a ceramic material. The cylindrical tube is flared outwardly at one end as at 2 to receive thin mica sheet or window 3 which is sealed gas-tight to tube 1 by means of a low melting point glass 4. Generally the mica window varies in weight from about one to five milligrams per square centimeter, the lower weight or thinner material admitting softer radiation. The end of the tube opposite the mica window 3 is also sealed gas-tight. Mounted within the tube along the major or longitudinal axis thereof is an elongated wire anode 5 of chromium-iron alloy, tungsten or other suitable metal which passes through the tube wall as shown and thus is made externally accessible. The diameter of this wire may vary, usually being about five to fifty mils. A glass bead 6 is normally fused to the inner end of anode 5 to prevent leakage of the discharge from the sharp point which in turn would prevent the wire from attaining along its entire length a proper voltage gradient. An electrically conductive coating 7, produced by treatment with tin chloride as described above, covers the inner surface of tube or envelope 1 as shown and serves as the cathode. Making electric contact with the cathode coating 7 is a split ring or band 8 of metal such as stainless steel which fits tightly within the periphery of coating 7. This band, as well as all other metal parts exposed to the counter atmosphere, is polished and oxidized to prevent corrosion or absorption of the halogen content of the atmosphere. Wire 9 is electrically joined to ring 8 by any convenient means and passes through the wall of the tube as shown. The atmosphere in the tube which is generally maintained at a pressure of from five to fifty centimeters of mercury is made up of a halogen and other inert gas or gases, a typical composition being one part by volume of halogen to 760 parts by volume of neon and four parts by volume of argon.

The mica window used in some counters may also advantageously be coated with the metal

oxide film of this invention to conduct off electric charges which collect on the mica surface during operation of the device and may produce faulty operation or false impulse signals.

Another modification of the tube is shown in Fig. 2. This tube has no mica window, the radiation to be measured passing directly through the relatively thin side walls 11 of the tube which are coated on their inner surface with a conductive surface film 12 as described herein. Wire anode 13 is mounted longitudinally in the tube and passes out of the tube through a gas-tight seal. The usual glass bead 14 is fused to the inner tip of anode 13. Electrical contact is made with the cathode coating 12 in any convenient manner. For example, a split ring or band 15 of polished and oxidized metal such as stainless steel may be slipped inside the tube before it is sealed and lead wire 16 fixed thereto and passed through the tube wall as shown.

In Fig. 3 there is illustrated a schematic circuit for an ionization detection device of the present type which is represented by cathode shell 18 and anode wire 19. A source of potential, V, is provided in series with the counter to maintain the atmosphere in the device at a potential which will cause rapid production of ion pairs upon introduction of ion-producing radiation. Resistance R and a capacitor C as shown complete the circuit to the detecting means which may be an electrometer, amplifier or other means for giving a signal to register the impulse generated by ionization-producing radiation. Upon the entry of ionization-producing radiation into the atmosphere of the device through the mica window or tube wall, one or more ion pairs are formed. The electrons so formed collide with other gas atoms enroute to the anode and in effect cause an avalanche of electrons to be swept to the positive electrode. The resulting electrical impulse flows through the circuit and registers in the detecting means.

There is produced by following the teachings of this invention an ionization detection device which may operate efficiently with corrosive halogen-containing atmospheres. The halogen-absorbing surfaces are reduced to a minimum and so constancy of halogen content and detection performance is insured. The device described also has a minimum number of glass to metal seals and avoids sharp metal edges which produce arcing or corona effects.

What we claim as new and desire to secure by Letters Patent of the United States is:

1. An ionization detection device comprising a non-conducting, vitreous envelope containing an atmosphere of ionizable gases including a halogen, an anode within said envelope, a cathode comprising a non-metallic film of electrically conductive corrosion-resistant metal compound on the inner surface of said envelope, said film being non-corroding in the presence of a halogen gas and being obtained by applying a metal halide to the inner surface of said envelope while said surface is maintained at a temperature above the boiling point of said metal halide, and externally accessible terminals connected with said anode and cathode.

2. An ionization detection device comprising a vitreous envelope containing an atmosphere of ionizable gas including a halogen, a wire anode within said envelope, a non-metallic electrically conductive film comprising a tin compound on the inner surface of said

envelope, said film being non-corrosive in the presence of a halogen gas and being obtained by applying a tin halide to the inner surface of said envelope while said surface is maintained at a temperature of from 400 to 700° C., and externally accessible terminals connected with said wire and coating.

3. An ionization detection device comprising a closed gas tube having a mica window at one end thereof and containing an ionizable atmosphere of chlorine, argon and neon, an elongated wire anode mounted within said tube along the major axis thereof, a cathode coating of a non-metallic tin compound which is non-corroding in the presence of chlorine on the inner surface of said tube, said cathode coating being obtained by applying a tin chloride to the inner surface of said envelope while said surface is maintained at a temperature of from 400 to 700° C., and externally accessible terminals connected with said anode and said cathode.

4. An ionization detection device comprising a closed glass tube containing an atmosphere of chlorine, neon and argon, a wire anode mounted within said tube along the longitudinal axis thereof, a cathode coating of a non-metallic iron

compound which is non-corrosive in the presence of chlorine gas on the inner surface of said tube, said cathode coating being obtained by applying an iron halide to the inner surface of said envelope while said surface is maintained at a temperature above the boiling point of said iron halide, and terminals connected with said anode and said cathode and passing through said tube.
